REFRIGERATING APPARATUS

Earl D. Drake, Grand Rapids, Mich., assignor to
Nash-Kelvinator Corporation, Detroit, Mich., a
corporation of Maryland

Application September 18, 1942, Serial No. 458,827

2 Claims. (Cl. 20—35)

The present invention relates to refrigerating cabinets, and more particularly to a door construction for such cabinets.

It is an object of the present invention to provide an improved door for a refrigerator cabinet having inner and outer panels in spaced apart relation whereby the outer panel is rigidly reinforced and stiffened to support the weight of the door without buckling or twisting, and the inner panel is mounted in free floating relation thereto.

It is another object of the present invention to provide an improved door construction in which the desired rigidity is obtained by use of cross straps or braces.

It is a further object of the present invention to provide a door construction having adjustment means for aligning the door in sealing arrangement with a wall of a cabinet to prevent air entering through the opening to a compartment in the cabinet closed by the door.

The invention itself, however, both as to its organization and its method of operation, together with additional objects and advantages thereof, will best be understood from the following description when read in conjunction with the accompanying drawing, in which:

Fig. 1 is a side view of a refrigerator cabinet embodying the present invention;

Fig. 2 is a fragmentary plan view of a refrigerator door embodying the present invention with parts broken away and parts shown in section;

Fig. 3 is a fragmentary enlarged cross sectional view taken along line 3—3 of Fig. 1;

Fig. 4 is a fragmentary enlarged cross sectional view taken along line 4—4 of Fig. 2; and

Fig. 5 is a fragmentary perspective view of a strap used in the present invention.

Shown in the drawing is a refrigerator cabinet 15. The cabinet has a food storage compartment refrigerated by a suitable refrigerating apparatus of which the condensing unit is mounted in a machine compartment insulated from the food storage compartment, and to which access is had through door or panel 17.

Access to the food storage compartment is had through door 20 mounted by hinges 22 to a side wall of the cabinet. The door is provided with a rubber gasket 24 adapted to seal against the front wall of the cabinet immediately adjacent to and about the opening to the food storage compartment to prevent air entering the compartment.

The door comprises an outer panel or shell 28 of sheet metal and an inner panel 27 spaced from the outer panel for the insertion of heat insulation material 29 therebetween. The inner

panel 27 is preferably formed of "Bakelite," "Micarta," or other plastic or compositional material having a low heat conductivity.

The outer panel 26 is of pan like conformation having top and side walls 30, and bottom wall 32. The top, sides and bottom walls are bent inwardly to form a peripheral ledge 34 about the door. The metal is extended from the ledge 34 to form a second ledge 36 in parallel continuation below the ledge 34. Secured by weld, or the like, to the ledge 36 is a frame 37 extending about the door and serves as a box-like reinforcement frame structure. The inner marginal edge of the frame is bent at right angles to form a rearwardly extending flange 39.

Secured adjacent to each of the upper corners of the door to the frame member 37 by their ends 41 are straps 40. The straps are crossed to extend diagonally across the door and are secured at 20 their opposite ends to the bottom wall 32 of the outer panel. The straps are formed of relatively thin metal having the end 41 offset to provide a shoulder 42. The opposite end is doubled over to be secured by weld, as at 44, to the main 25 portion of the strap forming a triangular shaped loop 45. Formed in the base 46 of the loop 45 is an opening through which extends an internally threaded nipple 47 having an enlarged base or head portion 49 resting flush on the base 46. The nipple is fixedly secured in the strap by indentations 50 formed in the sides of the triangular loop 45 to project over the head portion 49 to prevent withdrawal or undue axial movement of the nipple. Turning or rotation of the nipple is 30 prevented by forming the portion 49 rectangular so as to engage the upwardly extending sides of the loop.

Openings are formed in the bottom wall 32 of the door in which are pressed cup shaped members 52 having an opening 54 formed in the bottom thereof. Extending through opening 54 to thread in a nipple 47 is a screw 56 having an enlarged head 57 adapted to lie in the cup 52. The cups are positioned adjacent opposite ends of 45 the bottom wall of the door to permit anchorage of a respective strap thereto by a screw 56. The rotation of each screw increases or decreases, depending upon the direction or rotation, the tautness of each strap to provide the correct tension for correcting any warping or buckling tendency of the outer panel.

The opposite end 41 of each strap is secured by bolt and nut 59 to the rear side of the frame member so that the shoulder 42 is in abutment 55 against the flange 39. As the screw 56 is rotated

to draw the strap taut the shoulder 42 serves to direct the force against the frame and prevent shearing of the end 41 on the bolt, or the cutting of the bolt by the strap.

The door gasket 24 is secured to the door by means of an integrally formed tongue 60 adapted to lie upon the frame 37. The tongue is secured to the frame by strip 62 attached by screws 63 to the frame. The tongue 60 is formed with an enlarged end portion 65 against which is held the inner door panel 27 by the portion 67 of the gasket which extends around and over the marginal edge portion of the inner door panel. The gasket 24 also seats upon the ledge 34. By this arrangement the inner door panel is mounted in a floating relation.

In the mounting of the door to the cabinet the gasket 24 should seal tightly against the face of the cabinet about the opening to the food storage compartment. Should, for example, it be found that the left hand corner of the door be away from the cabinet to prevent a tight seal, the threading of the screw 56 in the opposite diagonal corner, the right hand corner, will increase the tautness of the strap to flex inwardly the corner of the outer panel sufficiently to move the gasket against the face of the cabinet. Likewise, should the door seal too tightly against the cabinet along one portion to prevent another portion from sealing, a rotation of the screw in the opposite direction will effect sufficient decrease in the tautness of the straps to relieve the undue stresses on the panel. Each strap may be individually tightened or loosened relative to the requirement of the panel.

By the use of cross straps, relatively thin sheet material may be used in the forming of the outer panel. The cross-bracing reinforces the panel against buckling, twisting or warping. By the individual adjustability of each strap the panel may be flexed to align the door gasket with the face surface of the cabinet, and by the tension of the strap upon the screw so as to draw the head in frictional contact with the cup to prevent undue rotation of the screw, the panel is held in the fixed rigid position thereafter. The adjust-

ment screws are so located in the bottom wall of the door so as to permit easy access thereto, and at the same time are so hidden from view as not to interfere or detract from the external appearance of the cabinet.

While I have shown and described the preferred form of my invention and that form described in detail, it will be apparent to those skilled in the art that various modifications may be made therein without departing from the spirit of the invention or from the scope of the appended claims.

I claim:

1. A door of the class described comprising inner and outer panels with heat insulation therebetween, said outer panel formed of relatively thin sheet material of pan-like conformation including top, side and bottom walls bent inwardly to form a peripheral ledge about the door, a frame secured to said ledge and extending about said door to stiffen the outer panel, straps extending diagonally across said door within said insulation, one end of each strap fixedly secured to said frame and their opposite ends having individual adjustable means for securing to a wall of said outer panel, each of said adjustable means independently operable to tighten a respective strap sufficiently to stiffen said outer panel into a fixed rigid position.

2. A door of the class described comprising inner and outer panels with heat insulation therebetween, said outer panel formed of relatively thin sheet material having sides directed toward the inner panel, a frame secured to said sides to stiffen said outer panel, straps extending diagonally across said door within said insulation, one end of each strap fixedly secured to said frame member, separate means for securing each of the opposite ends of said straps to one of said inwardly directed sides of said outer panel, each of said means being individually and independently adjustable to tighten its respective strap sufficiently to stiffen said outer panel into a fixed rigid position.

EARL D. DRAKE.
